SPACE DISCHARGE TUBE

Filed Sept. 29, 1931

FIG. 1

FIG. 2

FIG. 3

INVENTOR

August Hund

BY

Wm. J. Herdman

ATTORNEY

UNITED STATES PATENT OFFICE

AUGUST HUND, OF WEST ORANGE, NEW JERSEY, ASSIGNOR TO WIRED RADIO, INC., OF NEW YORK, N. Y., A CORPORATION OF DELAWARE

SPACE DISCHARGE TUBE

Application filed September 29, 1931. Serial No. 565,761.

My invention pertains in general to space discharge tubes and specifically relates to that type of space discharge tube utilizing glow or ionization discharge.

5 One of the objects of my invention consists in providing a tube for producing space conduction between cold electrodes by gaseous ionization.

Another object comprises providing a non-
10 thermionic space discharge tube having electrodes disposed in a manner such as to reduce inter-electrode capacitance to a minimum.

I accomplish these and other desirable objects by a novel construction of space dis-
15 charge tube having electrodes non-axially disposed in a containing envelope having an attenuated gaseous atmosphere.

In the drawing which accompanies and forms a part of this specification, and in
20 which like reference numerals designate corresponding parts throughout:

Fig. 1 is a perspective view of one embodiment of the construction of the space discharge tube of my invention;

25 Fig. 2 is a fragmentary view showing the relative position of the electrodes employed in my space discharge tube when viewed from the top; and

Fig. 3 is a fragmentary view of the relative position of the electrodes when viewed from the side.

30 My invention contemplates providing a construction of space discharge tube for producing space conduction by ionization in which electrodes are constructed and positioned in a manner such as to reduce inter-electrode capacitance to a minimum, whereby the space discharge tube can be effectively used in communication systems, particularly for the production of oscillations. In my co-
35 pending application, Serial Number 561,837 filed September 9, 1931, I have disclosed the circuits employed with such a tube for producing sustained high frequency oscillations for signaling purposes.

Referring to the drawing in detail and particularly to Fig. 1, there is provided a containing envelope 1 which may be composed of any suitable material such as glass or fused quartz. This envelope 1 is provided

with presses 2 and 3 positioned on opposite sides of the envelope. An extruded portion 4 of the envelope 1 is provided to permit of the sealing off of the envelope from a vacuum system. In accordance with my invention the envelope 1 is substantially exhausted and filled with a suitable gas at a desirable pressure. In experiments I have determined that helium at a pressure of substantially 55 12 mm. of mercury produces satisfactory re-
60 sults for the purposes indicated.

Electrodes 5 and 6 are sealed in the presses 2 and 3, respectively, and extend externally of the envelope 1. These electrodes 5 and 6 are formed of round metal rods, the ends of 65 which are reduced to form flat spatulate portions 7 and 8. These rods may be composed of nickel or other suitable material.

It will be noted from Fig. 2 that the plane of the major surface of the flat portion 7 of electrode 5 is substantially at right angles to the plane of the major surface of the flat portion 8 of electrode 6. Further as shown in Fig. 3, the flat portion 8 forms an obtuse angle with the axis of the electrode 6, where-
70 by but one corner of the spatulate portion 8 is proximate to the spatulate portion 7 of electrode 5 to form a small gap across which 75 gaseous ionization takes place. It will be further noted from Fig. 3 that the electrodes 80 5 and 6 are non-axially disposed with reference to each other.

The foregoing construction and arrangement of electrodes provides for minimum inter-electrode capacitance. I have found in 85 my experiments that the conditions described provide for the efficient production of relaxation oscillations when a suitable potential difference is applied to the electrodes. In experiments when producing oscillations, it was 90 noted that the ionization discharge occurs in the form of an enveloping glow along which-ever electrode may have a negative potential with respect to the other electrode. In accordance with my invention this glow or 95 space discharge is brought about by gaseous ionization between electrodes which are substantially cold as compared with the well known thermionic emissive electrodes.

Although I have shown one embodiment of 100

my space discharge tube it will, of course, be obvious to those skilled in the art that changes can be made therein without departing from the intended scope of my invention. I do not therefore desire to limit myself to the foregoing except insofar as may be pointed out in the appended claims.

What I claim is new and original and desire to secure by Letters Patent of the United States is:

- 10 1. A space discharge tube comprising, an envelope with an attenuated atmosphere of gas therein and a plurality of electrodes within said envelope having respectively adjacent spatulate end portions disposed in different planes with respect to each other.
- 15 2. A space discharge tube comprising, an envelope with an attenuated atmosphere of gas therein and a plurality of rod-like electrodes within said envelope having respectively adjacent spatulate end portions disposed in different planes with respect to each other.
- 20 3. A space discharge tube comprising, an envelope with an attenuated atmosphere of gas therein and a pair of rod-like electrodes within said envelope and extending from substantially opposite sides thereof having respectively adjacent spatulate end portions disposed in different planes with respect to each other.
- 25 4. A space discharge tube comprising, an envelope with an attenuated atmosphere of gas therein and a plurality of electrodes having respectively adjacent spatulate end portions disposed in different planes with respect to each other and further non-axially disposed with respect to each other within said envelope.
- 30 5. A space discharge tube comprising, an envelope with an attenuated atmosphere of gas therein, a pair of electrodes within said envelope having respectively adjacent spatulate end portions, one of said spatulate portions being formed at an angle with respect to its respective electrode to present a small area of spatulate portion proximate to the other of said electrodes.

AUGUST HUND.
